UNITED STATES PATENT OFFICE.

DANIEL W. PEDRICK, OF PHILADELPHIA, PENNSYLVANIA.

METAL-BORING MACHINE.

SPECIFICATION forming part of Letters Patent No. 255,449, dated March 28, 1882.

Application filed December 20, 1881. (No model.)

To all whom it may concern:

Be it known that I, DANIEL W. PEDRICK, of the city and county of Philadelphia, in the State of Pennsylvania, have invented certain new and useful Improvements in Apparatus for Boring Cylinders, of which improvements the following is a specification.

My invention relates to cylinder-boring mechanism of the class in which a boring-bar, carrying a cutter-head and cutters, is supported and rotated in bearings secured removably to the ends of a cylinder, and receives a slow longitudinal movement to impart the desired feed to the cutters by gearing operated by the rotation of the boring-bar and connected to a nut engaging the thread of a stationary feed-screw. Such a construction is exemplified in Letters Patent of the United States No. 66,011, granted and issued to L. B. Flanders, under date of June 25, 1867, upon which my invention is an improvement, its objects being to economize space and render the apparatus self-contained by dispensing with an exterior support for the feed-screw, and to enable the boring-bar and cutters to be readily moved into any desired position relatively to the feed-screw.

To these ends my improvements consist in the combination of a bearing-plate for the boring-bar, adapted to be connected to one end of the cylinder which is to be bored, a bearing or thrust plate having a central socket for the reception of the end of the feed-screw, and coupling-rods having their ends secured to the bearing-plates of the boring-bar and feed-screw, respectively.

My improvements further consist in the combination, with the boring-bar and feed-screw, of a sectional or divided nut pivoted to one of the gears by which longitudinal movement is imparted to the boring-bar, and a removable clamp by means of which said nut may be made to engage with or be removed from contact with the feed-screw, as desired.

The improvements claimed are hereinafter more fully set forth.

In the accompanying drawings, Figure 1 is a longitudinal central section through an apparatus for boring cylinders embodying my invention; Fig. 2, a face view of the bearing-plate of the feed-screw; Fig. 3, an end view, on

an enlarged scale, of the nut of the feed screw clamped in position upon the screw and connected to the gear by which it is rotated; and Fig. 4, a side view, on a similar scale, of one section of said nut.

The boring-bar B, which is tubular for the major portion of its length, is supported and turns freely in sockets c, secured in the central openings of bearing-plates C, bolted to brackets C', which are in turn bolted to the flanges 55 of the cylinder A, which is to be bored. A cutter-head, B', is secured upon the boring-bar by a key, b', fitting a longitudinal slot in the bar, and carries a series of adjustable cutters, b. Rotation is imparted to the bar by a gear, B², secured thereon by a key, b², said gear being by preference driven by a train of gearing mounted in bearings in a frame, B³, journaled upon the hub of the gear B². The construction of said gearing is, however, not 60 material to my improvements, and need not therefore be herein specifically set forth.

A feed-screw, D, fits freely within the tubular portion of the boring-bar B, and is supported in a sleeve, e, projecting from one side of 75 a frame or feed-casing, E, which carries the bearings of the train of gearing by which the boring-bar is moved longitudinally to effect the feed of the cutters. The outer end of the feed-screw D is fitted, so as to prevent its rotation, in the central socket of a bearing or thrust plate, D', which is connected by coupling-rods d with the bearing-plate C of the adjacent end of the cylinder A. Collars d' are formed upon the coupling-rods d, against which 80 the plates C and D' bear, the portions of the rods exterior to said collars passing through slots in said plates and having threaded ends and nuts d², by which they are clamped to the plates. The sleeve e of the feed-casing is provided with a key or feather, which enters a longitudinal groove in the feed-screw, so as to prevent the rotation of the casing upon the screw, while admitting of its longitudinal movement, and the boring-bar is fitted to rotate freely upon the outer surface of said sleeve 85 as a journal. A gear, b³, secured upon the outer end of the boring-bar, engages a gear, e', journaled upon the feed-casing, and the gear e' in turn engages a gear, e², upon a hollow 90

100

shaft, e^3 , fitted in bearings in said casing. The gear e^2 may be made fast or loose upon the shaft e^3 , as desired, by means of a sliding stem, e^4 , fitting within the shaft, and having a transverse-pin which enters radial slots in the gear e^2 , the stem being held in its normal position to effect the coincident rotation of the gear e^2 and shaft e^3 during the boring operation by a spring. A gear, e^5 , secured upon the shaft e^3 , engages a gear, e^6 , which is journaled on the feed-casing concentrically with the feed-screw and boring-bar, and is rotated at a reduced rate of speed by and coincidentally with the boring-bar through the gears b^3 , e^7 , e^2 , and e^5 . The train of gear-wheels, as above described, is substantially similar in arrangement and operation to that of Letters Patent No. 66,011, before referred to, and does not *per se* constitute part of my invention.

20. A sectional or divided nut, F , composed of two sections, each having an internal thread corresponding with that of the feed-screw, is pivoted by bolts f to the gear e^6 in such relation to the feed screw as that when the two 25 sections are brought into contact and connected by a clamping nut, f' , fitting an external thread on the sections, they form a complete nut, which engages the thread of the feed-screw. Inasmuch as the feed-screw is held 30 stationary and the feed-casing is prevented from rotating upon it, the rotation of the gear e^6 and nut F moves the casing and boring-bar longitudinally upon the feed-screw, thereby imparting the required feed to the cutters.

35. When it is desired to move the boring-bar backward to its original position, or to so adjust it that the cutter-head may stand in any desired position relatively to the bearing-plates of the boring-bar, the clamping-nut f' is removed and the sections of the nut F swung upon their pivots, so as to be clear of the feed-screw, when the boring-bar may be readily 40 and speedily moved by hand to the required position, the delay which is involved in trav-

ersing the nut backward over the feed-screw, 45 as in the construction heretofore employed, being obviated. The sections of the nut F are herein shown as separately pivoted to the gear e^6 ; but, if desired, one may be made to partially overlap the other, and a single pivot can 50 in such case be employed.

By my improvements I provide an apparatus which is complete in itself and needs no support or bearing exterior to the cylinder which is to be operated upon, thus economizing the 55 space occupied and facilitating application under circumstances where the location of an external bearing for the feed-screw is not conveniently practicable. It will be seen, also, that economy of time is effected and convenient 60 operation promoted by the means provided for admitting of the quick return of the boring-bar to position for commencing a new cut, or to any other desired position.

I claim as my invention and desire to secure 65 by Letters Patent—

1. In an apparatus for boring cylinders, the combination, substantially as set forth, of a bearing-plate having a central opening for the passage of a boring-bar, a bearing or thrust 70 plate having a central socket for the reception of a feed-screw, and coupling-rods by which said plates are connected one with the other.

2. In an apparatus for boring cylinders, the combination, substantially as set forth, of a 75 boring-bar, a feed-screw concentric therewith, a gear journaled upon a casing which is fitted to move with the boring-bar longitudinally on the feed-screw without rotating with the boring-bar, a sectional or divided nut pivoted to 80 said gear, and a clamp by which said nut may be made to either engage with or be removed from contact with the feed-screw.

DANIEL W. PEDRICK.
